SHEET DIAPHRAGM FOR RAILWAY CARS

Larry A. Hansen, Philadelphia, Pa., assignor to
The Pennsylvania Railroad Company, Philadelphia, Pa., a corporation of Pennsylvania

Application August 2, 1940, Serial No. 349,443

5 Claims. (Cl. 105—15)

This invention has reference to flexible diaphragms for railway car passageway connections and more particularly to the mounting of the side diaphragm intermediate the ends of coupled cars or between the ends of such cars and relatively spaced face plates. A serious disadvantage inhering to prevailing sheet diaphragms is due to the fact that the edge holding or clamping means invariably conduces to tearing and breaking down of the juncture, this objection being more pronounced when the diaphragm consists of sheet rubber with the vertical side edges reinforced or enlarged to provide substantial holding means.

The primary object of this invention is to overcome the noted disadvantage by provision of a novel holder means for the supported edges of sheet diaphragms which effectively prevent tearing and other rupturing over long periods of time or extended usage.

Another object is to provide a holder means including a spacer rib which when brought into diaphragm securing relation imposes a higher degree of compression on the edge reinforcement than upon the adjoining sheet whereby the tensile strength of the latter part remains substantially constant for the "life" of the rubber.

Other objects, with ancillary advantages of this invention will become apparent from the following detailed explanation of the preferred embodiment thereof, typically illustrated by the accompanying sheet of drawings, wherein like reference characters designate corresponding parts in all the views; while the concluding claims more particularly define the features of novelty over the prior art.

In the drawing:

Fig. 1 is a transverse section through one side of a typical car end and vestibule construction including the present improvements.

Fig. 2 is a cross-section, on a larger scale, lengthwise of the sheet diaphragm and associated holding means; and,

Fig. 3 is a similar enlarged scale section through the diaphragm before fixture between the adjoining ends of coupled cars.

In describing the form of this invention exemplified in the single sheet of drawings herewith, specific terms will be employed for the sake of clarity, but it is to be understood the scope of said invention is not thereby limited; each such term being intended to embrace all equivalents which perform the same function for an analogous purpose.

55 Referring more in detail to the drawing which

illustrates the adaptation of this invention to a railway car vestibule diaphragm arrangement, such as forms the subject-matter of a companion application filed concurrently herewith under Serial No. 349,442, the railway car end is comprehensively designated by the numeral 4, the same including vestibule and corner posts 5, 6, respectively; while 7 is the inner face plate and 8 the side wings hinged thereto at 9 in accordance with known practice, whereas 10, 11 are the inner and outer flexible diaphragms.

The means for influencing the wing 8 outwardly and constantly imposing tension of the diaphragm 11 comprise springy leaf-members 12 rigidly secured to the vestibule post outer flange 13 by means 14, said leaf-members having their outer ends pivotally attached at 15 to slidable shoes 16 carried by the wing 8, all in conformity with the above identified companion application for patent.

In accordance with the instant improvements, the outer diaphragm 11 is conveniently of sheet rubber with the vertical side edges preferably formed as rectangular-section substantial ribs 17 which may be reinforced by a "duck" surrounding strip 18 inserted during fabrication of said ribs; and such ribs may also have a fillet juncture 19 as shown to best advantage in Fig. 3. For attaching the diaphragm 11 intermediate the car body corner post 6 and the outer flanged edge 20 of the opposing wing 8, use is made of special sections 21. Each such section 21 embodies a web portion 22 with rectangularly related paralleling flanges 23, 24 and 25, the two former 23, 24 being of equal size, whereas the latter 25 is outwardly bent to define a flanking lip 26 in a plane paralleling the outer edges of the flanges 23, 24 for a purpose later explained. In addition, the web portion 22 of each section 21 intermediate the flanges 23, 24 is provided with spaced holes 27 for passage of clamp bolts 28, fitted with lock-washers 29 and nuts 30, whereby the sections 21 are rigidly attached to longitudinal projections 31 from the corner post 6 and the opposing flange edge 20 integral with the wing 8 outer vertical edges. It is also to be observed the cross-section of the diaphragm ribs 17 is of a depth relatively greater than that of the special section flanges 23, 24, and the plane of the section lip 26, determined so that when the clamp bolts 28 are tightened-up a definite degree of compression is imposed evenly lengthwise of the diaphragm ribs 17 with a substantially less degree of compression similarly lengthwise of the diaphragm adjoining the fillet 19, while the section 35

flanges 23, 24 being of equal depth positively prevent any rocking or other movement of the sections 21 relative to the parts to which they are clamped.

5. From the foregoing the merits and advantages of this invention will be clearly understood, while it will be apparent that changes in the shape and relative proportions of the parts of the sections 21 may be varied without departure from 10 the spirit and scope of said invention as defined in the following claims.

Having thus described my invention, I claim:

1. In vestibule construction for mobile cars having projecting end flanges and spacially-related wings with angled edge flanges, the combination of a flexible sheet diaphragm having the car end and wing adjoining edges formed as substantial ribs; a special section attached to each car end projecting flange and the confronting wing flange, such section including adjoining grooves defined by a web portion with spaced outer and an intermediate flanges; one of said grooves serving to receive an edge rib of the diaphragm and having its outer flange bent to 25 provide a lip for cooperation with the diaphragm body, and said intermediate flange with the other outer flange positively securing said section against rocking movement with respect to the car end or wing flange, and means associated 30 with the other groove for attaching the special section to the aforesaid car end flange and the wing flange.

2. In vestibule construction for railway cars including corner posts with longitudinally projecting end flanges, and spacially related wings having the outer vertical edge portions flanged toward the car end; the combination of a flexible sheet outer diaphragm having the car end and wing adjoining edges embodying substantial ribs 40 of rectangular cross-section; means in the form of special sections attached to the car corner post flanges and wing edge flanges, each such section embodying a web portion with outer and an intermediate flanges jointly defining parallel grooves; one of the grooves being cooperative with the corner post flange or a wing

flange and of a depth to receive a rib edge of the diaphragm, said groove having its outer flange longitudinally bent to form a lip for similar coaction with the diaphragm body portion adjoining said rib, the intermediate flange being 5 effective to positively prevent rocking movement of the section; and means, associated with the other groove, for attaching the special section to the aforesaid car end flange, or to the confronting wing flange, with concurrent clamping compression of the diaphragm rib and adjoining body portion.

3. The combination of claim 2, wherein the special section flanges defining the groove for the attaching means, and the lipped one, are 15 respectively of differential depth relative to the diaphragm rib and the body portion so as to impart contrasting degrees of compression on said rib and its adjoining body portion when secured to the car end or wing flanges. 20

4. The combination of claim 2, wherein each special section embodies a web portion with rectangularly related paralleling outer flanges and an intervening flange, one of the outer flanges and said intervening flange being of equal depth 25 to define spaced edges for grip coaction with a corner post flange or a wing flange to prevent relative movement, and spaced holes lengthwise of the section web intermediate the second mentioned flanges for passage of suitable clamping 30 means.

5. As a new article of manufacture, an attaching section, for flexible sheet railway car vestibule diaphragms, embodying parallel channels defined by spaced outer flanges and an inner flange, one 35 of the outer flanges and said inner flange being of equal depth with the free edges in a common plane, spaced holes in the web portion between said equal depth flanges for passage of securing means, and the other outer flange being longitudinally bent to define a lateral lip in spacial 40 parallelism inwardly with respect to the common plane edges of the first mentioned outer and inner flanges.
